UNITED STATES PATENT OFFICE.

REINHARD T. TORKELSON, OF WARREN, MASSACHUSETTS.

EJECTOR MECHANISM FOR FIREARMS.

SPECIFICATION forming part of Letters Patent No. 715,903, dated December 16, 1902.

Application filed April 25, 1901. Serial No. 57,364. (No model.)

To all whom it may concern:

Be it known that I, REINHARD T. TORKELSON, of Warren, county of Worcester, and State of Massachusetts, have invented an Improvement in Firearms, of which the following description, in connection with the accompanying drawings, is a specification, like letters on the drawings representing like parts.

10 The present invention relates to extractor and ejector mechanism for guns of the breakdown type, and is shown as embodied in a single-barreled shotgun.

15 The object of the invention is to simplify the ejector mechanism, so as to obtain a device which will operate satisfactorily without materially increasing the expense of construction.

20 In accordance with the invention the extractor, which co-operates with the flange of the shell in the usual way, is mounted in a suitable guide in the barrel-lug and is provided with a spring, the tendency of which is to move the extractor in such a direction as to force the shell out of the chamber. The said extractor is normally held in place against the stress of the said spring by means of a catch which is arranged to be operated upon by a catch-actuator or tripping device in 25 response to the movement of the barrel with relation to the frame when the gun is broken down or opened. Both the catch and the tripping device are movably mounted in a recess in the barrel-lug below the extractor-guide.

30 In accordance with the invention the frame is provided with an undercut recess for the barrel-lug, the shoulders at the top of the said recess co-operating with the tripping device to release the ejector when the barrel has 35 been tipped down far enough to permit the shell to clear the breech-block.

40 The tripping device is shown as pivotally mounted, and the pivot-pin is arranged to extend laterally beyond the barrel-lug and constitutes a stop to prevent the barrel from being tipped beyond a certain point, the engaging portion of said tripping device being so related to the said pivot that it will be acted upon just before the said pivot is stopped, 45 thus releasing the ejector. This stop prevents any further movement of the tripping device, so that the movement of the catch is

limited, and the said catch may be arranged to co-operate with a second engaging portion of the ejector to limit the movement thereof 55 and hold the same against the stress of the spring after the ejector action.

Figure 1 is a longitudinal section of a device embodying the invention, the gun being shown as closed; Fig. 2, a similar view showing a gun broken down or open; Fig. 3, a transverse section showing the gun closed; Fig. 4, a modification, and Fig. 5 a perspective view of the tripping device alone.

50 The extractor-rod *a*, which is also utilized as an ejector, is mounted in a guide-bore *b* in the barrel-lug *B* and is acted upon by a suitable spring *b*², herein shown as a spiral spring, interposed between the end of the extractor-rod and the end of the guide-passage. 70 The said extractor-rod is held against the stress of said spring by means of a catch *c* in such a position that the shell-engaging portion *a*² will not act to any material extent upon the shell, the spring *b*² thus being kept 75 under tension, and the said catch *c* is movably mounted in the barrel-lug and normally stands in the path of a shoulder *a*³, formed on the under side of the extractor-rod *a*. As indicated in Figs. 1 and 2, the said catch *c* 80 consists of a vertically - movable plunger mounted in a guide bore or opening *B*² in the barrel-lug and capable of being moved toward and from the extractor, so as to engage or disengage the shoulder *a*³. The said catch 85 is arranged to be acted upon by a tripping device *d*, which is pivotally supported in the barrel-lug, the pivotal support being shown as afforded by a transverse pin *d*², which extends completely through the barrel-lug and 90 projects beyond the same at one or both sides. In the construction shown in Figs. 1 and 2 the said tripping device has a projection *d*³, which enters a suitable recess in the plunger *c*, and the tripping device *d* is also 95 acted upon by means of a spring *d*⁴, the tendency of which is to rock the tripping device upon its pivot in such a direction as to force the catch *c* toward the extractor-rod *a*. With the parts in normal position, therefore, the full action of the spring *b*² upon the extractor-rod is prevented by the said catch *c*, which is in the path of the shoulder *a*³.

To get the proper ejector action, it is nec-

essary that the parts should remain substantially in this condition until the gun has been nearly opened, the extractor-rod then being released, so that the spring gives it a sudden impulse, which results in kicking the shell clear of the chamber. To perform this operation, the tripping device d is shown as provided with tripping projections d^5 , which extend laterally beyond the sides of the barrel-lug, and the frame A of the gun is provided with an undercut recess A^2 , the projecting shoulders A^3 of which overlie the tripping projections d^5 , so as to engage the same when the gun is broken down and the lug moved upward in the recess.

The pivotal support d^2 is so arranged with relation to the tripping projections d^5 as to engage the shoulders A^3 as soon as the projections have been moved far enough to withdraw the catch c from the shoulder a^3 . In order that the said catch may constitute a stop to limit the outward movement of the ejector—that is, to prevent the same from flying clear of the barrel—the said ejector is provided with a second shoulder a^4 , in the path of which the catch c stands when the gun has been opened as far as the stops d^2 will allow.

It is advantageous that the shell should be loosened in the chamber prior to the action of the spring b^2 , which might otherwise lack sufficient strength to force a shell out if it were stuck in the chamber to any extent. This may be accomplished, as herein shown, by providing the tripping device d with a projection d^6 , extending into the path of a shoulder a^5 , formed on the extractor-rod a , the first movement of the tripping device when the barrel is broken down positively forcing the said projection against the said shoulder, so as to move the extractor-rod just enough to loosen the shell without materially relieving the tension of the spring. The catch c normally stands far enough in front of the shoulder a^3 to admit of such slight movement, the ejector member being held, of course, when the gun is closed by engagement with the breech-block.

The catch may obviously be supported in the barrel-lug in any suitable way, a modification being shown in Fig. 4 in which the catch c^{10} is pivotally supported upon a pin c^3 , which extends transversely through the lug, the action being the same as in the construction already described.

55 I claim—

1. Extractor and ejector mechanism comprising an extractor longitudinally movable

in the barrel-lug and provided with a spring; a catch movably supported in the barrel-lug below said extractor and adapted to hold the same against the stress of its spring; a tripping device independent of but coöperating with said catch, said tripping device also being movably supported in the barrel-lug; and an undercut recess in the frame, the upper surfaces or shoulders of which are adapted to coöperate with a projecting portion of the said tripping device when the barrel is tipped, as set forth.

2. The combination with the frame provided with an undercut recess for the barrel-lug; of an ejector mounted in the barrel-lug and provided with a spring; a catch for said ejector also mounted in the barrel-lug; a tripping device for said catch mounted on a transverse pivot-pin in said lug, the ends of the said pin projecting beyond the sides of the said lug to coöperate with the upper or overlying surface of the undercut recess in the frame and afford a stop for the barrel; and a projection of said tripping device also projecting beyond the side of the barrel-lug to engage the upper surface of said recess before it is engaged by the pivot-pin, substantially as described.

3. The combination with the ejector provided with a spring; of a catch for said ejector consisting of a plunger mounted in a suitable bore in the barrel-lug and coöperating with a shoulder on the ejector; a tripping device pivotally supported in said barrel-lug and coöperating with said catch; and an undercut recess in the frame, the upper or overlying surface of which coöperates with the tripping device to release the ejector, substantially as described.

4. The combination with the ejector provided with a spring; of a catch for said ejector to hold the same in position against the stress of said spring; a tripping device for said catch mounted in the barrel-lug and having a projection underlying the upper surface or overlying portion of an undercut recess in the frame; and a portion of said tripping device to engage and positively actuate said ejector prior to the tripping of the catch, substantially as described.

In testimony whereof I have signed my name to this specification in the presence of two subscribing witnesses.

REINHARD T. TORKELSON.
